UNITED STATES PATENT OFFICE.

ERNEST W. TAYLOR, OF CLEVELAND HEIGHTS, OHIO, ASSIGNOR, BY MESNE ASSIGNMENTS, TO INDUSTRIAL BROWNHOIST CORPORATION, A CORPORATION OF OHIO.

APPARATUS FOR REMOVING RAILROAD BALLAST.

Original application filed February 21, 1927, Serial No. 169,967. Divided and this application filed June 22, 1927. Serial No. 200,672.

My invention relates more particularly to means for excavating and removing the ballast of railroad beds that lies between the inner ends of the ties of two adjacent tracks, and, a primary object of the invention is to provide an efficient apparatus that will perform all its functions without any part of the same projecting beyond the median line between two adjacent tracks, one 10 of which is being occupied by the said apparatus, so that no train on the said adjacent track need be slowed down or stopped because of its proximity and operation.

A further object is to so correlate the several coating units of the apparatus that the whole will be within the confines of the cross sectional outlines, established by railroads, with respect to clearances. This requirement must be met absolutely and in- 20 exorably adhered to, and renders the problem one of exceptional difficulty.

A still further object of my invention is to provide an apparatus wherein grab or clamshell buckets without flexible connections to their supporting means may be used as the excavating element.

Grab buckets are found, by experience, to be better adapted for the purpose than the endless chain buckets, or other types of excavators such as generally characterize patented efforts to provide ballast-removing means.

Another object of my invention is to reduce the time now required or taken for removing a given length of track ballast; as any tying-up of tracks for other than their designed purpose works a hardship on train schedules, it will be readily understood that an apparatus of the kind in question must 30 perform its functions expeditiously as well as continuously as a whole. By the nature of the elements embodied and employed in my invention, this objective is attained.

In an application by me filed February 45 21, 1927, and bearing Serial Number 169,967, I showed and described drawings and specifications for the most part identical with those herein, and claims corresponding with the claims in this application, and

also claims covering other features de- 50 scribed. Under the regulations of the Patent Office a divisional application was accord- ingly required which is hereby made.

As to all matters, therefore, herein shown and described, but not claimed, and which were claimed in said application filed February 21, 1927, I hereby disclaim the same in favor of said former application as forming no part of the invention sought to be secured by the present application. 55 60

In the drawings Fig. I is a plan view of two adjacent railroad tracks, upon one of which is movably mounted an apparatus which contains an adaptation of my present invention; Fig. II is a sectional view of the road-bed taken on the line *a*—*a* of Fig. I showing the road-bed and the apparatus in side elevation; Fig. III is a side elevation of the apparatus with two dirt-cars flexibly attached to a standard railroad locomotive; Fig. IV is a cross-section on the line *b*—*b* of Fig. I, with the excavating member about 65 70 75 to dig; Fig. V is a top view of Fig. IV, except that the trolley is shown in the upper limit of its travel; Fig. VI is a side elevation of Fig. IV; Fig. VII is a cross-section on the line *c*—*c* of Fig. I, and Fig. VIII is an end elevation of the rearward end of the apparatus.

1 and 2 are railroad tracks. 80
A is a platform or car-body mounted upon rails 1^a—1^a of the track 1.

f and *r* designate, respectively, the forward and rearward ends of the car-body A.

Near the forward end of the platform or car-body A are two spaced apart frame-structures B and B', made up, respectively, of vertical posts 3—4—5—6 and 7—8—9—10 and the requisite struts and cross members. These structures support excavating buckets 85 90 together with mechanisms for operating the same.

Suspended from the structures B and B' are trolley tracks or bucket guides G and G', respectively. As the guides are alike a 95 description of one only will be given. The gauge of the bucket guide track is determined by the grab bucket employed, which,

by reason of the principle of its operative construction, when descending along said tracks must be open and therefore requires a clearance between its digging or spade members and the members of the track that constitute the rails. The members of the track, in this case, are channels with their flanges turned toward each other. As will be apparent the channel sections of the tracks G and G', by their oppositely arranged flanges, further serve sufficiently to enclose the trucks, and thereby retain the same in their normal relations against the force of gravity.

15 The guide G' is pivotally connected to the frame B' between the posts 7 and 8, and, the rear posts 9 and 10 by means of the pins O, O, at the upper ends of the posts 8 and 10. As stated above, the gauge of the tracks is determined by the "spread" of the bucket, which, indirectly also determines the distance between the front posts 7 and 8, and, the rear posts 9 and 10. This distance must be great enough to accommodate the guides G and G' 20 and, of course, always be wider than said spread. The track members or channels g—g' are held to gauge by yokes y and a hinge or pivot strut h that is rigidly connected to the track members g—g' at their 25 pivotal ends. The track or bucket-guide G' extends from the pivots O—O, above the car floor, over and downwardly between and beyond the side posts 7 and 9 to a point at the side of the car-body that is somewhat below 30 the floor of the same, and within the space defined by the median line of the tracks. To assist the yokes to keep the track from spreading rubbing plates p—p are located on the outside of the channel members g—g', 35 between the yokes y—y, to contact with the inside of the posts 7 and 9. Extending laterally from the car, at the elevation of the floor of the same, are rigid track bracing members d—d'. These bracing members, in 40 alignment with the posts 7—8 and 9—10, are within the cross-sectional outline allotted to cars for standard railroad equipment. Rubbing plates p'—p' are provided at the 45 lower ends of the guide G' to contact with the braces d—d'.

50 Provision is made to house or stow the bucket guides G and G' within the required cross-sectional area when the apparatus is idle or in transit. To this end connecting rods C—C are pivotally attached to the lower ends of each track member g—g' at c' and extend inwardly and are pivotally connected at their inner ends to crank mechanisms M—M. These crank mechanisms are 55 connected together by means of a longitudinal through shaft S. As will be observed, upon referring to Fig. IV, the bucket guides may be adjusted outwardly when occasion 60 requires.

65 Trolleys T, T, which carry and sustain

excavating members E, E', are made up of two spaced apart channel members e—e that extend between the track members g—g' to points where they meet trucks t—t' to which they are pivotally connected by means of extended truck axles t^a—t^a. Flanged truck wheels t², t², t², t², are adapted to travel between the flanges of the track members g—g'. By extending the axles t^a—t^a of the trucks t and t' and utilizing them as pivots for the 70 trolley T a distinct advantage is gained over pivoting the trolleys to the trucks at any other points thereon, for the reason that the nearer the pivotal points are to the front or downward end of the trucks, the shorter the 75 track-members can be made.

80 The excavators E E' may be of any standard two-rope type or design of digging bucket, but, as said, the grab bucket type seems precisely fitted for the uses herein 85 pointed out. Such buckets are simple in construction, strong, positive in action, and unlike other forms of excavators in the art concerned, may be related to the car-member of a combination, and worked laterally of the 90 same, without undue tortuous strains upon such, or other members or parts. The spades, when spread, are vertical, or nearly so, and, when so lowered on the material, their penetrative effect is at a maximum and such as 95 to insure, first, a full purchase for the load, and, then, under the principle of their construction, the maintenance of the initial depth as the material is drawn together in the bucket. In material of the kind in question, therefore, the excavation left by each 100 load-gaining operation, is always a prism-shaped cavity of well and uniform proportions, and the method of removing such material, which emphasizes a trench formation 105 in the process, may be effectively carried out by the use of the special kind of excavator as herein pointed out.

110 Whatever the kind of bucket used, however, it must be of such width that there will be no danger of interference with trains passing on the adjacent track, and, further, it will be understood, as the term excavating bucket is used herein, it is intended to comprise any suitable self-filling digging bucket 115 whether the same is of the class usually referred to as two-rope, or single-rope, coal, ore, stone, grab or clamshell bucket, or, whether or not the blades of the same are specially equipped with teeth to increase 120 their penetrative effect.

125 Some railroad companies see fit, or have occasion, to remove the ballast, for renovation, or other purposes, only from between adjacent tracks, but other companies require the ballast to be taken up that lies on the outer tracks of a plurality track system, or that the sides of a single track system known as "shoulders" be removed.

130 As these shoulders have a pronounced

slope or inclination away from the tracks it will be readily seen that a grab bucket when flexibly connected to its support (as by means of the operating ropes according to the custom in all rope operated buckets) cannot be advantageously employed to excavate the ballast along the shoulders because the bucket will careen and topple the moment it strikes the "shoulder" when lowered onto the same. By the unique manner in which the bucket is connected to the supporting trolley in this invention, it cannot careen or topple, but a substantially upright position is insured for the same, and always maintained, which makes it an excellent instrumentality for excavating under the conditions explained.

As shown, the top-block member of the excavator is pivotally connected to the trolley T in such manner as will permit it to swing or oscillate in a longitudinal direction.

By connecting the grab bucket E directly to the trolley T, as said, another distinct advantage is gained, namely; the weight of the trolley and trucks is carried by the bucket when its digging edges strike the ground, thereby giving the digging force, or power, necessary or desirable for excavating ballast, or other refractory material, that has lain in place for a number of years.

The usual bucket sustaining and operating ropes are employed. The bucket closing rope CR is reeved in the customary manner, i. e., it leads from the hoisting drum D over a deflecting sheave S' in the upper part of the frame structure to and around the top and bottom block sheaves that are part of the bucket proper. The bucket sustaining rope SR is led from its hoisting drum D' over a second deflecting sheave S², (beside the sheave S') to the trolley beam T where it is securely fastened.

A plow supporting frame PS is located in the car-body between the frames B and B'. It is slidably mounted on ways W W for lateral adjustment. The plow support PS carries a plow-beam PB obliquely mounted in the same, on the guide rollers r' r'; roller r² is provided to keep the beam PB against the rollers r' r'. The beam is further provided with a rack R adapted to be engaged by the gear and pinion mechanism R' on the plow support PS. The lower end of the plow-beam PB is bent from the oblique to the horizontal and engages the top side of a plow PP. The plow and beam may be retracted to the position shown in dotted line (see Fig. VII) by means of the rack and pinion mechanism and a lateral adjustment screw V.

Upon the car platform, at one side of the longitudinal median line thereof and under the range of travel of the excavators, is located a conveyor K. It extends from the

front end of the platform in parallel relation with the floor thereof to a point just to the rear of the frame-structure B' from which point it proceeds upwardly and rearwardly to a gravity screen X which is near the rear end of the platform, and which is adapted to receive the fouled ballast discharged onto the conveyor by the excavators E, E'. The screen X is inclined from the conveyor K downwardly to the rear until it meets the top of a bin Y at the rear of the platform. The bin Y is adapted to receive the screened ballast from the screen X and to retain or discharge the same into the excavations made by the excavators E E'. A means Z for disposing of the screenings from the screen X is shown as being adapted to discharge the same into convenient railroad cars RC, RC, which are provided with conveyors K' for distributing the screenings into the several cars for the purpose.

There are several ways of propelling the apparatus while it is performing its renovating functions, as by traction through its supporting truck-wheels, by outside power such as a locomotive, and by pulling as by means of a cable and winch, the winch being located on the car-body and the free end of the winch's cable being fastened to some anchorage. Figure III illustrates the cable and winch idea. A winch W' is located on the front end of the car A and a cable W² leading from the winch's drum is anchored to a locomotive L at a distance ahead of the apparatus. A power generating unit U is indicated near the rear end of the car A.

To operate the apparatus after it has been taken to the site, it is first necessary to project the lower end of the bucket guides G—G' outwardly from their retracted or traveling positions, by means of the crank mechanism M to positions that will permit the buckets or excavators E, E' to clear the ends of the ties when lowered for digging. An excavation is now made by the front or head bucket E, the bucket is then hoisted to the dumping position where its load is discharged, in the present instance, onto the conveyor K. After the first excavation is made the apparatus is advanced (by any means) substantially a distance not to exceed the spread of the bucket and stopped; while the apparatus is being moved to this second digging position, the plow PP is introduced into the excavation first made and forced toward the ties of the adjacent track until it has reached the position shown in Fig. VII, the rear bucket E', however, is not brought into play until such time as it can reach and excavate the material that the plow has forced or deflected into the trench made by the head bucket. The buckets now should work in unison. The conveyor K receives the fouled ballast from the excavators and carries it to the screen X.

X where it is screened, the screened ballast falling into the receiving bin Y and the screenings dropping to a boot Z' of the elevator Z, which, in turn discharges them onto a conveyor on railroad cars RC, that are provided for the purpose. The gate of the bin is kept closed to confine the screened ballast until the chute is brought above the excavated spaces when it is opened and kept open during the renovating process.

It will be observed that because of the design of the guides G and G' no racking mechanism is required, and with the novel correlation of the bucket and trolley, excavations can be made rapidly, two to three per minute.

As the apparatus is advanced and stopped for successive excavations during the bucket hoisting, dumping, and lowering operations progress can be made expeditiously.

Inasmuch as the apparatus as a whole is advanced and stopped for each successive excavation, while the bucket, with its load, is being hoisted to the car, the load there dumped, and the bucket is being lowered for another excavation and load, among other advantages, a marked economy of time, and expedition of operation, is thereby effected.

It will be understood that although the wheeled structure, or platform, that supports certain of the mechanisms and instrumentalities that are necessary and desirable, is shown as a unitary construction, such construction is intended to be within the invention claimed, although that feature is divided up into, or composed of two or more, platforms or cars for the convenience of operation.

What I claim and wish to secure by Letters Patent, is:

1. In an apparatus for removing material in place between adjoining railroad tracks and raising the same to a wheeled platform, or car-body on, and adapted to traverse one of said tracks, the combination, with such platform, of an elevated frame-structure thereon, trolley tracks, spaced apart through their lower portions to a width greater than the spread of the excavating bucket herein-after named, pivotally connected to the upper part of said structure, and extending above the platform over and downwardly along the side of the same to a predetermined point above said material, a trolley mounted on said trolley tracks with its frame, or body member, between and pivotally connected to the wheel-trucks of the same, a material excavating bucket longitudinally pivoted to the trolley, means, on said frame structure, for raising and lowering the trolley along its tracks, means thereon for operating the bucket through its designed functions, and means on the downwardly extending portion of said trolley tracks for retaining the trucks in normal re-

lations to their respective tracks when lowered to said portion, substantially as shown and described.

2. In an apparatus for removing material in place in the space between adjoining railroad tracks and raising the same to a wheeled platform, or car body, on, and adapted to traverse one of said tracks, the combination, with such platform, of an elevated frame-structure thereon, trolley tracks, spaced apart through their lower portions to a width greater than the spread of the excavating bucket herein-after named, connected to the upper part of said structure, and extending above the platform over and downwardly along the side of the same to a predetermined point above said material, a trolley mounted on said trolley tracks with its frame, or body member, between and pivotally connected to the wheel-trucks of the same, a material excavating bucket longitudinally pivoted to the trolley, means on said frame structure for raising and lowering the trolley along its tracks, and means thereon for operating the bucket through its designed functions, substantially as shown and described.

3. An apparatus for removing ballast in place at the side of a railroad track and raising the same to a platform, or car, on and adapted to traverse the track, comprising such platform, a trolley-track thereon pivotally fastened at one end to and above the floor of the same and leading over and downwardly along the side of the car to a predetermined distance above said material, a trolley on and adapted to traverse said trolley-track, an excavating bucket longitudinally pivoted to the trolley, means on the platform for raising and lowering the trolley along its tracks, and means thereon for operating the bucket through its designed uses and functions, substantially as shown and described.

4. An apparatus for removing ballast in place at the side of a railroad track, and raising the same to a platform, or car, on, and adapted to traverse the track, comprising such platform, a trolley-track thereon spaced apart to a distance greater than the spread of the excavating bucket herein-after named, and fastened at one end to and above the floor of said car and leading over and downwardly along the side of the car to a predetermined distance above said material, a trolley on and adapted to traverse said trolley-track, an excavating bucket longitudinally pivoted to the trolley, means on the platform for raising and lowering the trolley along its track, and means thereon for operating the bucket through its designed uses and functions, substantially as shown and described.

5. An apparatus for removing ballast in place at the side of a railroad track and

raising the same to a platform, or car, on, and adapted to traverse the track, comprising such platform, a trolley-track retractably mounted thereon at a predetermined height above the floor, and leading downwardly therefrom over and along the side of the car to a predetermined distance above said material, a trolley on and adapted to traverse said trolley-track, an excavating bucket longitudinally pivoted to the trolley, means on the platform for raising and lowering the trolley along its track, and means thereon for operating the bucket through its designed uses and functions, said trolley-track being spaced apart at its downwardly extending portion to a distance greater than the width, or spread, of said bucket, substantially as shown and described.

6. In an apparatus for removing material in place in the space between adjoining railroad tracks, and raising the same to a wheeled platform, or car-body, on and adapted to traverse one of said tracks, the combination, with such platform, of an elevated frame-structure thereon, spaced apart trolley-tracks connected to the upper part of said structure and extending above the platform over and downwardly along the side of the same to a predetermined point above said material within the median line of said space, a trolley mounted on said trolley-tracks with its frame, or body-member, between and pivotally connected to the wheel trucks of the same, an excavating bucket longitudinally pivoted to the trolley, means on the frame structure for raising and lowering the trolley along its tracks, and means thereon for operating said bucket through its designed functions, said trolley-track being spaced apart at its downwardly extending portion to a distance greater than the width, or spread, of said bucket, substantially as shown and described.

7. An apparatus for removing ballast in place at the side of a railroad track, comprising a supporting platform movably mounted on said track, carrying a pair of excavating buckets lowerable over and down the side thereof, in alignment with each other, upon the ballast next adjoining the track, means carried by said platform projectable outwardly therefrom for reaching and progressively breaking up the ballast beyond the working range of said buckets, and deflecting the same into the cavities successively excavated by the forward member of said pair of buckets in the path of the rearward member thereof, means on the platform for lowering, raising, dumping, and otherwise operating the buckets in their designed movements, and means thereon for projecting said breaking up and deflecting means, to and from the platform, substantially as shown and described.

8. In an apparatus for removing ballast

material in place in the space between adjoining railroad tracks and raising the same to a wheeled platform, or car-body, on and adapted to traverse one of said tracks, the combination with such platform, of a plurality of elevated frame-structures thereon, trolley tracks pivotally connected to the upper part of said structures respectively, extending above the platform over and downwardly in alignment with each other, along the side of the platform to a predetermined point above said material and within the median line of said space, a trolley mounted on each of said trolley-tracks with its frame, or body member, between and pivotally connected to the wheel trucks of the same, an excavating bucket longitudinally pivoted to each said trolley, an obliquely disposed plow slidably mounted on the platform rearwardly of the foremost of said structures, and means for laterally adjusting and retracting the same with relation to the platform, means on said structures for raising and lowering their trolleys along said tracks, and means thereon, in each case, for operating the buckets pertaining thereto through their designed functions, said trolley-tracks being spaced apart at their downwardly extending portions to a distance greater than the width, or spread, of said buckets, substantially as shown and described.

9. A method of removing ballast material in place between adjoining railroad tracks consisting in the separate and successive excavation of uniform and connected areas of a strip of said material along the side of one of said tracks, hoisting the material as so excavated to and upon a car movably mounted on said track and discharging the same at such point, alternately with such excavating, hoisting and discharging operations and without occupying clearance spaces for overhanging cars on the other of said tracks, breaking up and deflecting into the cavities left by said excavations the portion of said material in place between each successive cavity and said other track, and, simultaneously with each said successive excavating, hoisting and discharging operations, a similar excavating, hoisting and discharging operation of the material broken up and deflected, as aforesaid, substantially as shown and described.

10. The described method of removing ballast from its place between the ends of the cross-ties of adjoining tracks, and transferring the same to a wheeled truck on one of said tracks, consisting in successively excavating at equidistant points, or intervals thereof, a connected series of substantially uniform and unitary sections of and making up a rectangular strip or portion of said ballast material along said track; moving said truck progressively along the track to said points of excavation; simultaneously

with said movements of the truck, plowing or otherwise dislodging and deflecting into the cavities made by said excavations, the portions of the ballast material in place
5 bordering on said cavities; successively excavating from said cavities the material deflected therein; raising the material as ex-

cavated from said strip and said cavities, to said truck and discharging the same when so raised, substantially as shown and described. ¹⁰

In testimony whereof I hereunto sign my name.

ERNEST W. TAYLOR.
